Daniel Garish.

Letters Patent. Granted April 11th 1806.

The Schedule referred to in these Letters Patent and making part of the same, containing a description in the words of the said Daniel Garish himself of his improvement in the Saw-mill.

To All Men & May, concern: Be it known that I Daniel Garish of this month in the State of New Hampshire have invented certain improvements in the construction of saw-mills and I do hereby declare that the following are full and exact descriptions thereof, referenced being had to the drawings which accompany and make a part of this specification: Fig. 1. is the accompanying drawing of an elevation of the saw-yard and its appurtenances, as seen sideways of the Mill, a portion of the framed work being removed to exhibit the construction of the several parts in a more distinct manner. Fig. 2. is an elevation of the saw-yard and other parts in both figures, where the same parts are shown they are indicated by the same letters. A. is the saw-frame which is moveable up and down by means of the crank B. B. being as seen in the drawing, a crank on each end of the crank shaft and two pins A. A. leading from them, on to each side of the saw-frame, by which I attach them by a joint pin, at a considerable height, say, at, or above the middle of the frame, by which means the pins may have sufficient length to operate advantageously with a much less elevation of the floor of the mill than is usually required. This saw-frame does not slide in fixed posts, but is quiet, with vibrations by the sockets D. D. which are fitted to, and slide upon the round rods E. E. The sockets D. D. are made to vibrate upon guides or joint pins in the manner shown in the drawing, instead of being immovably attached to the saw-frame, as this frame besides its vibratory motion up and down, has one also backwards and forwards, which is given to it in a way and for the purpose to be, now described. The upper and lower guides or Fig. 1. A. A. & 2. E. E. B. B. also the inner guides B. B. Fig. 1. and 2. instead of being attached to the fixed posts to any part of the framed work of the mill is affixed to the vibrating posts E. E. being by pins at their upper ends to the posts E. E. as seen in the several figures. This vibrating post, receives their motion from the eccentric mill operating like the works

for opening and closing the valves in Steam Engines or may be operated with the application of Coms Fig. 1. & 2. II. By these means the backward and forward vibration above spoken of is given to the saw frame, and the saws as they descend are thrown forward against the wood to be cut, whilst in ascending they are made to recede from it so as to give clear of an obstruction and to allow a free passage for the escape of the saw dust. It will be obvious to every mechanist that the feed of the saw in this manner may be regulated either by varying the eccentric, or the swing of the lever P. P. instead of the eccentric a cam, capable of easy regulation (See Fig. 1. & 2. I.) may be employed to produce the vibration; it may also be produced by other means well known to mechanist. Besides the lever P. P. are two others, one of which is shown I and this may be denominated the feed lever. They may be regulated by extending the arm of the eccentric to the lever by a separate connecting joint at a, which being made more liable will adjust the feed, this may also be done by a moveable fulcrum, or joint pin at b. The catchet wheel made down in the under side of the catchet wheel as shown in the drawing must be brought against it by springs or by counter weights as by extending them and giving them sufficient weight on the opposite side of the fulcrum. The carriage is moved forward in the usual way by a pinion, is lantern on the catchet wheel shaft, taking into cog with both its under side and K on a firm and loose pulley or drum upon the crank shaft, as I prefer to give motion to the saw by means of a strap upon the carriage back. I employ a chain band C which passes round a wheel d. on the crank shaft, which is coupled by means of a clutch to the loose pulley K and then round out of gear by a lever which may be rendered self acting or may be moved by hand; the chain band passes also round a pulley on the shaft of the catchet wheel and pinion. The feed bands must of course be disengaged from the catchet wheel when the carriage is run back, it is not necessary however to particularize such things as are understood by every competent manager of a saw mill. When gangs of saws are used I employ straps to strain them which effect the purpose in a very perfect and rapid manner admitting of a change of the number and arrangement of the saws in a more ready way than by the plan hitherto adopted. The lower ends of the saws are fastened by haws in the usual way but the straps at the upper end are tightened by means of screws, and for the purpose of applying these in the best manner, and also to stiffen the saw frame, I employ two

or mortise heads or cross timbers as L and M, into its sides or cheeks to which the stumps may be alternately attached and upon which they are to be retained by screws passing through the cross heads, which screws at the upper ends of the staple straps. Further brace them by iron braces above and below it, calculating from the centre of the frame from an acute angle with its top and bottom and meeting in an obtuse angle in the middle, the timber which occupy the usual place of the fender posts in ordinary saw mills from parts of a galloper or independent frame to which a little support is given, if the movements are attached, they are independent of the frame of the mill house, by which means that excessive vibration which is so destructive to such buildings is completely avoided. What I claim as my invention in this invention is first the employment of two cranks and sprocket, the latter attached to the saw frame in the way described, by which among other advantages the force of the mill may be placed considerably lower than usual. Secondly the manner in which I arrange and fix the guides of the saw frame in combining the swiveling sockets with the eccentric guide rods behind the saw frame. Thirdly, the application of the eccentric or eccentric roller analogous eccentric upon the crank shaft for the purpose of rotating the saw frame backwards and forwards through the intermediate lever to which the two guide rods of the saw frame are attached or both as are passed by wheel, means I am able to obtain this rotating motion in a circle much less than that of the sweep of the sprocket crank as may be desired. Further the manner of communicating the feed motion as derived from that of the eccentric and cranks and herein fully described. And I hereby declare that as this invention with all its complex machinery, may admit of numerous modifications, whilst the general principle of its construction and operation remains unchanged, I do intend by the foregoing claims to confine myself to the precise manner of fixing and arranging the individual parts as hereinafter laid down, but to vary the same as I may find convenient, whilst the same ends are attained by analogous means.

Mr. & Mrs. Walker
James Geddie

Daniel Gerish,
